UNITED STATES PATENT OFFICE.

MARCEL PERREUR-LLOYD, OF BOULOGNE-SUR-SEINE, FRANCE, ASSIGNOR TO MARIE VICTORINE BAILLY, WIDOW GARIN, OF PARIS, FRANCE.

APPARATUS FOR THE PRODUCTION OF ZINC, COPPER, OR OTHER METALS BY ELECTROLYSIS.

1,235,723.

Specification of Letters Patent. Patented Aug. 7, 1917.

Application filed May 24, 1915. Serial No. 30,243.

To all whom it may concern:

Be it known that I, MARCEL PERREUR-LLOYD, a citizen of the Republic of France, residing in Boulogne-sur-Seine, Department 5 of Seine, France, have invented certain new and useful Improvements in Apparatus for the Production of Zinc, Copper, or other Metals by Electrolysis, of which the following is a specification.

10 In order to obtain by electrolysis the deposit of metals free from rugosity and as smooth or glossy as possible it is desirable, as I have explained, especially in the specification of my application for Letters Patent 15 of the United States Serial No. 30,242, dated May 24, 1915, relating to the electrolytic production of zinc, to have means adapted to secure as far as possible a smooth and even deposit.

20 The present invention provides apparatus for attaining this result and the features of which will be seen from the following description of apparatus embodying the invention and from the claiming clauses, reference being had to the accompanying drawings in which

Figure 1 is a longitudinal section of the apparatus.

Fig. 2 is a plan.

30 Fig. 3 is an end elevation partly in section. Fig. 4 is a detail view on a larger scale of the driving mechanism at the left hand end of the shaft Fig. 1.

Fig. 5 is an end view of Fig. 4 with the 35 pulley removed.

Fig. 6 is a plan corresponding to Fig. 5.

Fig. 7 is a longitudinal view likewise on a larger scale, of the mechanism for actuating the rubbing pads.

40 Fig. 8 is a longitudinal section through the axis of this operating mechanism of Fig. 7.

Fig. 9 is a plan thereof.

Fig. 10 is a cross section of Figs. 8 and 9 45 taken on line M M.

Fig. 11 shows a detail of the mounting of the rubbers on their longitudinal rod.

Fig. 12 is a detail of the rod for carrying the rubbing pads.

50 Fig. 13 shows another detail.

Fig. 14 shows separately in face view the cam device for operating the pad carrier rod.

The apparatus forming the subject of the 55 invention, and which is suitable for the elec-

trolytic treatment of all metals, especially zinc, copper, etc., comprises a vat or tank A, preferably rectangular, which contains the electrolytic liquid and the electrodes. The cathode C is cylindrical and adapted to be 60 rotated. It is surrounded by the anode which envelops it almost entirely and which is itself formed in two parts, a lower part D and an upper part E fitting into the lower part. By this arrangement only the upper 65

part of the anode needs to be removed when it is required to withdraw the cathode cylinder C. The anode is formed of rods a of lead or other conducting material, such as carbon or cast magnetite, capable of withstanding anodic actions and attack. The rods a are united to the solid conductors or plates D E which are cast in molds in which all the rods a have been put in place before running the metal. This arrangement of 75

rods disposed in several rows and in staggered order, as seen in Figs. 1 and 3, has for effect to increase considerably the surface of the anode, that is to say the surface of depolarization, while allowing of a free 80 circulation of the electrolyte around the rotary cathode. The parts D E in which the ends of the anode rods a are held are stayed together at their upper part by intermediate 85 bars b and the end angle bars c c which rest on the upper edges of the tank A, so that the anode is freely suspended in the electrolyte.

The anode leaves a space F at top which has a twofold purpose; firstly it allows of 90 withdrawing the sheets of zinc or other metal deposited on the cathode when they have become sufficiently thick, without necessity for removing the upper part E of the anode or shifting the cathode cylinder 95 C; secondly this space F is also intended to permit of the longitudinal motion of the apparatus which serves for removing the bubbles of hydrogen that always tend to become deposited on the surface of the cathode cylinder, and also for rendering even and smooth the outer surface of the metallic deposit. This apparatus and its working 100 will now be described.

The said apparatus comprises fingers or 105 rods e mounted on a common rod G which extends the full length above the cathode. Each rod or finger e ends in a pad f formed of parchment skins insolubilized by immersion in aldehyde, acetone or other analo- 110

gous substance. The rods *e* of these rubbing pads are held by sleeves *g* made in two parts (see Fig. 11) clamped together by bolts *h*. The sleeves *g* next to the inner walls of the tank *A* also serve for connecting end to end the elements or parts of this pad carrier rod *G* (see the detail Fig. 12). This rod is in fact formed of three parts or sections, an intermediate portion *G* situated in the interior of the tank, and two end parts *G*¹. The end sleeves *g* unite these different parts together. When these end sleeves *g* are dismounted, the intermediate portion of the rod *G* is separated and this portion can then be withdrawn from the apparatus with the pad carrier sleeves *g* upon it, without necessity for dismounting these polishing pads individually.

The polishing pads *f* are reciprocated 20 on the upper surface of the metal deposited on the cathode, by means of the rod *G* on which they are all carried, this movement is transmitted to the rod *G* by a bell crank lever *i* *i*¹ the shorter arm *i*¹ of which ends in a ball or knuckle *j* connected by a link-like member in the form of a cylinder *j*¹ to another ball or knuckle *j*².

The lower ball *j*² is in fixed connection with a frame *v*. (see Fig. 14) in which turns 30 a cam *k* fast on a shaft *m* mounted in a special support *H* arranged in the neighborhood of the shaft *I* that carries the cylindrical cathode *C* and below the rod *G* that carries the rubbing pads. The two shafts *I* and *m* are connected by pulleys *J* and *J*¹ (Fig. 3). The rotation of the shaft *m* imparts motion by means of its cam *k* to the frame *v* pivoted at *x*, and the ball end *j*² of the frame *v* imparts longitudinal movement to the rod *G* and consequently to the pads carried on this rod. The cylinder *j*¹ contains at the ends (see the section Fig. 13) bearing members *z* *z* with spherical recesses or seats, and between the balls or knuckles *j* and *j*² is 45 fitted in the cylinder a cylindrical bearing member *Z*¹ with spherical recesses or seats fitting the said balls or knuckles.

The small shaft *m* carries a worm *o* gearing with a worm wheel *o*¹ carrying an eccentric stud *o*² on which the bell crank lever *i* *i*¹ is pivoted. According to the position occupied by the worm wheel *o*¹ the stud *o*² is raised or lowered to a greater or less extent. The drive or attack of the pad carrier rod *G* 55 by the arm *i* of the ball crank lever is therefore variable according to the position of the eccentric stud *o*², and to allow of this movement the sides of the fork of the arm *i* that acts on the end of *G*¹ *G* are formed with elongated grooves or slots allowing a certain play for the driver pin *i*². The consequence of this arrangement is that the starting and terminating points of the longitudinal reciprocating movement of the 65 rod *G* are continually modified or varied,

the result of which is that the pads *f* do not move between the same points and thus entire outer surface of the metal deposited on the cathode is rubbed, cleaned and polished successively; without this, striations would 70 be formed on the metal deposited on the cathode, and due to the rubbing pads always stopping and starting at the same places.

The cylindrical cathode is formed of a cylinder *G* the ends of which rest on two 75 rings *K* carried by arms *p* screwing at their ends into the rings *K* on the one hand and into the hubs *p*¹ on the other. Each of these hubs (see the detail Fig. 4) has on the inner side a screw threaded socket to 80 receive the threaded end of the intermediate portion *I* of the shaft; at the outer side this hub has a conical bearing or seat *q* smooth inside, and at the inner end of which is formed a screw-threaded hole *q*¹ to receive the end of a stud or end shaft member *I*¹ which fits accurately in the conical bearing *q* so that this stud or end member *I*¹ is very solidly fixed in alinement with the inside shaft *I*. 90

The same mounting of the shaft is effected at the two ends; each stud or end member *I*¹ passes through a stuffing box *I*²; the end of one of them carries the driving pulley *M*, and behind said pulley this stud *I*¹ or end member is supported in a ball bearing *I*³ connected by upper arms *r* to a plate *r*¹ bolted on the walls of the chamber *A*. The other stud or member *I*¹ at the other end of the apparatus carries the pulley *J* which 100 imparts the movement to the rubbing pads.

The end plates of the two ball bearings *I*³, at the ends of the cathode shaft, and which are in fact covers closing the said bearings, are fixed to these boxes *I*² respectively by 105 bolts *s* (see Fig. 5) and have arms or lugs *s*¹ with hooks or pins to receive the ends of springs *u* which act on the hooked ends of arms *u*¹ carrying the brushes *y*; these brushes bear on the studs or end shaft 110 members *I*¹ and lead the current from the cathode *C*, the current passing to the anode by the rods *c*¹ (Figs. 1 to 3).

The operation of this apparatus will be easily understood. When the circuit is 115 closed the current enters uniformly by the supports of the anodes, is distributed throughout the mass of the anode and passes out by the cathode, and the brushes *y* at the two ends *I*¹ of the cathode shaft, motion 120 being then imparted to the cathode by the pulley *M* the pulley *J* at the opposite end from the pulley *M* imparts rapid motion by the pulley *J*¹ to the shaft *m*, the worm on this shaft rotates the worm wheel *o*¹ 125 carrying the eccentric pivot *o*², the result of which is to vary continually the position of the bell crank lever *i* *i*¹ and therefore the point of attack of the rod *G* of the rubbing pads. At the same time the shaft *m* causes 130

the cam k to turn in the pivoting frame v , the terminal ball or knuckle j^2 of which acts on the bell crank lever i i^1 . Thus a reciprocating movement is transmitted to rubbing pad carrier rod G , the position of which is continually varied so that the pads uniformly rub the surface of the zinc deposited on the cathode, without leaving striations.

10 The apparatus above described may be employed for the electrolytic deposition of any metals other than zinc; in particular it may serve for the production of sheets of electrolytic copper.

15 Claims:

1. Apparatus for the production of metals by electrolysis, comprising a tank and a rotary cathode, a shaft on which said cathode is mounted, and means for supporting said cathode shaft, said means comprising a bracket adapted to be attached to the side of the tank, having a stuffing box in the wall of the tank for preventing liquid passing out around such shaft, and having outside of said tank beyond said stuffing box a bearing adapted to support said shaft.

2. Apparatus for the production of metals by electrolysis, comprising a rotary cathode, means for rubbing on the cathode, and means for imparting an irregular movement of said rubbing means lengthwise of the cathode.

3. Apparatus for the production of metals by electrolysis, comprising a rotary cathode, means for rubbing on the cathode, and means for imparting an irregular movement of said rubbing means lengthwise of the cathode, said means comprising a reciprocating rod, a lever for reciprocating said rod, and means for varying the fulcrum of said lever.

40 4. Apparatus for the production of metals

by electrolysis, comprising a rotary cathode, means for rubbing on the cathode, and means for imparting an irregular movement of said rubbing means lengthwise of the cathode, said means comprising a reciprocating rod, 45 a lever, and a pivot for said lever mounted upon a part and having an eccentric movement.

5. Apparatus for the production of metals by electrolysis, comprising a rotary cathode, 50 means for rubbing on the cathode, and means for imparting an irregular movement of said rubbing means lengthwise of the cathode, said means comprising a reciprocating rod, a lever, and a pivot for said lever, said 55 pivot being mounted eccentrically upon a shaft, a drive shaft having means for driving said shaft carrying the pivot, and means on said drive shaft for oscillating said lever.

6. Apparatus for the production of metals 60 by electrolysis, comprising a tank and a rotary cathode, a shaft on which said cathode is mounted, and means for supporting said cathode shaft, said means comprising a bracket adapted to be attached to the side 65 of the tank, having a stuffing box in the wall of the tank for preventing liquid passing out around such shaft, and having outside of said tank beyond said stuffing box a bearing adapted to support said shaft, and 70 brushes mounted upon said brackets, and adapted to bear upon said shaft, to conduct current from said cathode.

In witness whereof, I have hereunto signed my name in the presence of two subscribing 75 witnesses.

MARCEL PERREUR-LLOYD.
